UNITED STATES PATENT OFFICE.

ARTHUR ADKINS, OF LEICESTER, ENGLAND.

MEANS FOR DESTROYING ENEMY SUBMARINE CRAFT.

1,309,391.

Specification of Letters Patent.

Patented July 8, 1919.

Application filed March 7, 1918. Serial No. 221,000.

To all whom it may concern:

Be it known that I, ARTHUR ADKINS, subject of the King of Great Britain, residing at Leicester, in the county of Leicester, 5 England, have invented certain new and useful Improvements in or Relating to Means for Destroying Enemy Submarine Craft, of which the following is a specification, reference being had therein to the accompanying drawing.

This invention relates to means for destroying enemy submarine craft and comprises an arrangement of submarine mines for this purpose as will be hereinafter described.

The invention concerns explosive booms or like defence systems of the kind composed of connected mines and particularly that form where the drag or action of the 20 vessel upon the connecting means between the mines causes the latter to automatically assume a position in proximity to the sides or hull of the vessel prior to the explosion of the mines.

Booms of this character usually consist of a series or row of mines connected by a cable, the arrangement being floated upon or near the surface of the water or sunk to a certain depth.

Obviously for the purpose of protection against surface boats a boom of the kind referred to above must be somewhere near the surface of the water and in this position would not be suitable for intercepting submarine craft traveling submerged. To serve for protection against submarines traveling submerged the single series boom would require to be sunk to a certain depth but even when so arranged it might not be effective 35 against submarines traveling submerged at a greater or lesser depth. Hence with a system of connected mines such as referred to a multiplicity of the booms would be required in deep waters for affording adequate protection against submarine craft such booms being situated at varying depths 45 to form a vertical defensive system to intercept submarines at any depth.

The object of the present invention is to 50 form an explosive boom or defensive system of connected mines which will be effective at any depth and therefore appropriate for defensive purposes against submerged submarine craft or for catching and destroy- 55 ing same.

The invention consists of an explosive

boom or arrangement adapted for catching and destroying or for defensive purposes against submarine craft, characterized by vertical series of mines which are spaced 60 apart and anchored, the mines in each vertical series being connected, and one series being connected with another series by suitable connecting means (such as nets or cables) adapted to intercept submarine craft 65 traveling submerged and when engaged and dragged upon by such craft to draw one or more mines of the adjacent connected series into close proximity to said craft to facilitate the destruction of the latter by explosion of the mine or mines.

The distinguishing feature of the invention is that instead of using single mines connected together as by a cable, vertical series of connected mines are connected by 75 a net or a number of cables so that the arrangement will catch a submarine traveling at any depth, the mines in each vertical series being so spaced apart as to be situated at different depths for this purpose.

The connected vertical series are each so anchored as to admit of being readily dragged out of position when a submarine encounters the connecting means, thus allowing the mines to be drawn toward the 85 vessel without giving an indication in the latter that it is caught.

The mines employed are of the type which are exploded by contact. By using mines of this character premature explosion *i. e.* 90 an explosion of the mine before the latter has been drawn close to the vessel such as might occur in the case of a mine exploded by the pull on the cable and when the vessel was traveling slowly, is obviated.

To enable the invention to be clearly understood, reference will be made in the following further description to the accompanying drawing wherein is shown, by way of example, an arrangement of mines according to this invention suitable for the purposes already specified.

In the drawing:—

Figure 1 is a perspective view representing the arrangement of mines sunk into 105 position in the sea.

Figs. 2, 3 and 4 (drawn to a smaller scale than Fig. 1) are diagrammatical plan views illustrating the action of the connected series of mines when intercepting 110 and destroying a submarine as will be hereinafter described.

The arrangement represented in Fig. 1 consists of a number of submarine mines connected by cables 2 in such a manner as to form a plurality of vertical series 1^a, 1^b, 5 1^c and so on, each vertical series being anchored by a suitable weight 3 or other device. The vertical series of mines are connected together in pairs by means of nets 4 which extend from one series to another 10 as shown, it being observed that the connected pairs are separate from each other, for instance the series 1^b and 1^c form one connected pair, the series 1^a, 1^e another, the series 1^f, 1^g another and so on. It will also 15 be seen that the connected pairs of vertical series are positioned in such a manner that the openings between the unconnected series 1^a and 1^d, 1^e and 1^f, are covered by the connected pairs 1^b and 1^c, 1^f and 1^g, thus 20 while each connected series can operate independently of the others, no passage of a submarine through the arrangement is possible without contact with one or other of the connecting nets 4.

25 It will be understood that this arrangement of connected series of mines may be extended any distance so as to intercept the passage of a submarine at any depth providing the connecting nets and vertical 30 series of mines extend from the ocean bed to sea level or just below. The number of mines in each vertical series will of course depend upon the depth of water.

The operation of the arrangement is illustrated in Figs. 2, 3 and 4 where connected pairs of vertical series of mines as shown in Fig. 1, are represented in plan, 5 represents an enemy submarine traveling in the direction of the arrow its course being 40 shown by the dot and dash lines. As shown in Fig. 2 it approaches the arrangement of mines and is intercepted by the net 4 connecting the mines 1^b and 1^c which as the result of the submarine's contact therewith is displaced and draws with it the attached series of mines as shown by full lines in Fig. 3; the dotted lines indicating the original position of the two series and their connecting net. As the boat carries the net 50 4 forward with it the movement or way causes the mines by the drag of the net thereon to move inward toward the boat as indicated by the arrows in Fig. 3, until as the submarine continues on its course one 55 or more mines in one or both of the series swing into contact with the boat thereupon exploding and destroying the craft.

An arrangement such as described will be effective for the purpose of intercepting a submarine approaching it from either side and practically at any angle. The distance between the connected series of mines should not exceed one and a half or one and two thirds the length of a submarine in 60 order that no matter at what point between

the connected series the craft makes contact with the connecting means one at least of the mines will swing around on a radius shorter than the length of the boat and therefore come into contact with same. If 70 necessary the connecting net between the series of mines may be supported by one or more floats 6 (Fig. 1) and the net may be provided with anchoring means 7 at the bottom. Preferably the net is attached to 75 the connecting cables 2 and not to the mines themselves so as to be clear of the detonating horns of the mines.

The mines should be so placed as to allow 80 for a certain amount of movement which may be caused by currents and avoid contact of one series with another. The weights 3 or anchoring means should on the one hand be sufficiently heavy to retain the different series of mines in proper position but 85 on the other hand they should be light enough to yield to the drag effected by the contact of a traveling submarine with the connecting means between the mines. Obviously in determining the requisite weight 90 of the anchoring means, the strength of the prevailing currents (if any), the weight of the net or connecting means and cables as well as the buoyancy of the mines are factors which must be taken into consideration. 95

In another arrangement, not shown, a system of connected vertical series of mines to form a screen may be obtained by connecting a number of such series in a continuous row, but in such an arrangement the number of 100 series in the row must not be so great as to impede the movement of any pair of series toward the sides of the craft caused by the drag on the connecting means when the craft makes contact with same. 105

The system of connected mines herein described may be used to form booms for defending coasts, harbors and rivers, and while nets or cables are convenient forms of connecting means, the invention is not to be confined to such means, as other intermediate devices may be employed between the vertical series of mines to intercept submarines and when engaged by same draw the latter into contact therewith. 110

115 What I claim then is:—

1. An explosive boom adapted for catching and destroying submarine craft, comprising a plurality of vertical strings of mines, said strings being spaced apart from 120 one another and anchored, and connecting means between one string and another adapted to intercept submarine craft traveling submerged and when engaged and dragged upon by said craft, to draw one or 125 more mines of the adjacent connected strings into close proximity to said craft to facilitate the destruction of the latter by explosion of the mine or mines, substantially as described. 130

2. An explosive boom adapted for catching and destroying submarine craft, comprising a plurality of vertical strings of mines, said strings being spaced apart from one another, connecting means between one string and another adapted to intercept submarine craft traveling submerged, and anchoring means for each string of mines adapted to normally maintain said strings in position but to allow of the ready displacement of the same, when drag upon the connecting means by a traveling vessel occurs substantially as and for the purpose described. 10
3. An explosive boom adapted for catching and destroying submarine craft, comprising a plurality of vertical strings of mines, said strings being spaced apart from one another, means connecting together pairs of the vertical strings, adapted to intercept submarine craft traveling submerged, each connected pair of strings being separate from the others, and anchoring means attached to the strings of mines in each con- 15
- nected pair, adapted to normally maintain 25 said strings in position, but to allow of the ready displacement of the same, when drag upon the connecting means by a traveling vessel occurs substantially as and for the purpose described. 30
4. An explosive boom adapted for catching and destroying submarine craft, comprising a plurality of vertical strings of buoyant mines of the contact type, said strings being spaced apart from one another 35 anchoring means attached to each string, adapted to keep same in position but capable of being dragged under abnormal conditions, and nets connecting together the vertical strings in pairs, each connected pair being 40 separate from the adjacent pairs, substantially as and for the purpose described.

In testimony whereof I affix my signature in presence of two witnesses.

ARTHUR ADKINS.
